UNITED STATES PATENT OFFICE.

JOHN SHOSTROM, OF TACOMA, WASHINGTON.

SCRAPER.

1,192,127.

Specification of Letters Patent. Patented July 25, 1916.

Application filed July 13, 1915. Serial No. 39,569.

To all whom it may concern:

Be it known that I, JOHN SHOSTROM, a citizen of the United States, residing at Tacoma, in the county of Pierce and State of Washington, have invented certain new and useful Improvements in Scrapers, of which the following is a specification.

This invention relates to earth scrapers and has for its object the provision of means whereby when the scraper is drawn rearwardly the concave back plate and the scraper teeth will be protected and wear of the same avoided.

A further object of the invention is to so arrange the apron or protecting shoe that it will be automatically shifted to a position in rear of the scraper or below the same when a pull is exerted on the scraper to effect travel of the same.

20 The stated objects of the invention and other objects which will incidentally appear are accomplished in a mechanism such as is illustrated in the accompanying drawings, and the invention resides in certain novel 25 features which will be first duly described and then more particularly pointed out in the claims following the description.

In the drawings: Figure 1 is a perspective view of a scraper embodying my improvements, Fig. 2 is a longitudinal section of the same showing the parts arranged to permit rearward travel of the scraper, and Fig. 3 is a side elevation showing the parts in the position assumed when the scraper is 35 at work.

The scraper illustrated consists of side plates 1 and a concave back plate 2 connecting the rear edges of the said side plates. Draft cables 3 are attached to the front ends 40 of the side plates, and the back plate 2 has its lower edge projecting slightly below the lower edges of the side plates and extending forwardly, as clearly shown in Figs. 2 and 3. The said rear plate or back of the scraper 45 may be secured to the side plates in any convenient or preferred manner, and in the drawings, I have illustrated the said back as constructed with flanges 4 which fit against the inner surfaces of the side plates. 50 and are riveted or otherwise rigidly secured thereto. This construction, however, is illustrative only and any other preferred construction may be employed.

Along the lower edge of the back 2 are 55 secured the usual scraper or excavator teeth 21 and on the side plates are keeper plates

or brackets 22. Pivots 7 in the rear ends of said brackets support the standards or arms 6 which project upwardly adjacent the outer faces of the side plates and carry the apron 60 or runner plate 5, the pivots 7 being preferably at the center of the arc defined by the back 2 so that the said plate or apron may swing rearwardly to the position shown in Fig. 3 without binding upon the back or 65 being restricted by any interference with the back. The rear portion of the apron is curved upwardly, as shown at 8, and at the center of the said upturned portion, I secure the end of a cable 9 which passes upwardly 70 to and over a pulley 10 mounted upon the back 2 near the upper edge thereof and then extends forwardly above the scraper and is connected to the draft devices. I also secure to the rear edge of the apron or runner plate 75 other cables 11 which extend rearwardly therefrom to the engine.

It is thought the operation of the device will be readily understood from the foregoing description, taken in connection with 80 the accompanying drawings. When the scraper is at work to level the surface of the ground, the parts are arranged as shown in Fig. 3 and the scraper is drawn forward over the surface to be treated by power applied from the engine to the cables 3. The teeth 21 will, of course, take into the surface soil and cut off the projecting portions of the same, and the soil thus cut off will accumulate thereon and against the back 2. Inasmuch as the cable 9 is connected with the cables 3, the application of power to haul the scraper forward will draw the cable 9 to the position shown in Fig. 3 thereby lifting the apron or runner plate about its 85 pivotal connection with the side plates to a position in rear of the back 2. After the load has been discharged or the scraper has reached the end of its prescribed travel, a pull is exerted upon the cables 11 which will 90 cause the apron to swing downwardly and forwardly, the edge of the same striking the ground and serving as a fulcrum about which the entire device will be moved under the pull exerted upon the cables 11 until the 95 pivots 7 have reached a point in rear of the front edge of the apron whereupon the weight of the apparatus will cause the parts to return to the position shown in Fig. 2 100 under the influence of gravity. It will be 105 understood, of course, that the cables 3 and 9 are slack when a pull is exerted on the

cables 11 and that the continuance of the pull through the latter cables will draw the scraper rearwardly over the ground. In its rearward movement, the scraper will ride 5 on the apron and the back plate and teeth will be out of contact with the ground so that they will not be subjected to any wear.

My device may be applied to any scraper at a slight cost and will greatly prolong the 10 life of the same.

Having thus described the invention, what is claimed as new is:—

1. The combination with a scraper, of brackets secured to the sides thereof and offset therefrom, a runner plate, standards at 15 the ends of the runner plate intermediate the front and rear edges of the same and having their upper ends disposed between the sides of the scraper and the offset brackets, pivots inserted through said brackets and the upper ends of the standards into 20

the sides of the scraper, a pulley upon the rear end of the scraper near the top thereof, a draft cable connected to the front end of the scraper, a cable secured to and extending rearwardly from the runner plate, and a second cable secured to the runner plate and passing upwardly therefrom and forwardly over the said pulley and secured to the draft cable. 25

2. The combination with a scraper, of a runner plate, standards rising from the ends of the runner plate intermediate the front and rear edges thereof and having their upper ends pivoted to the sides of the 30 scraper, and means for moving the runner plate to a position in rear of the scraper or to a position under the rear end of the same. 35

In testimony whereof I affix my signature. 40

JOHN SHOSTROM. [L. S.]
